UNITED STATES PATENT OFFICE.

CHARLES W. GILLER, OF SHELBY, OHIO, ASSIGNOR TO THE SHELBY SALESBOOK COMPANY, OF SHELBY, OHIO, A CORPORATION OF OHIO.

AVIATOR'S MANIFOLDING LOG.

Application filed September 7, 1922. Serial No. 586,588.

This invention relates to recording devices such as ships' logs and the like and with respect to its more specific features to a log adapted for use in aviation and wherewith a plurality of records may be made at one writing.

One of the objects of the invention is the provision of a simple and efficient device of the character referred to in which manifolding sets of record leaves are effectively retained in designed position against chance of disturbance by strong air currents consequent from the use of the device in the open, as at sea or in a moving air ship; in which manifolding sets of record leaves are effectively retained in position for inscription and may be readily and quickly moved to and firmly held in stored position, in which they do not interfere with the inscribing of subsequent sets of leaves; in which the retaining devices are simple in construction and may be easily and quickly operated to permit the application and removal of record leaves.

Other objects will be in part obvious and in part pointed out hereinafter.

The invention accordingly consists in the features of construction, combinations of elements and arrangement of parts which will be exemplified in the construction herein-after set forth, and the scope of their application will appear in the appended claims.

In the accompanying drawing forming part of this specification and wherein similar reference characters refer to similar parts throughout the several views,

Figure 1 is a perspective view of a recording device embodying the invention, parts being broken away for clearer disclosure;

Fig. 2 is a side elevation of one of the main retaining devices;

Fig. 3 is an end elevation of a position of a main retaining device;

Fig. 4 is a detail, in plan, of a supplementary retainer;

Fig. 5 is a detail, partly sectional of another supplementary retainer;

Fig. 6 is a perspective view of one set of record leaves, detached and opened out to show their arrangement, the view being largely diagrammatic and on a smaller scale; and

Fig. 7 is a view of a detail.

Referring now more specifically to the

drawing the numeral 1 indicates a support. 55 This support may be a stiff flat plate of metal or other material, aluminum being preferred on account of its relatively light weight. As shown the support is rectangular in shape. On the support is a pad 2, 60 composed of a plurality of similar sets of superposed record leaves, the sets being likewise superposed relative to each other. Only two of the sets are illustrated, one set 65 in position for inscription, and the other set in stored position. The numerals 4 indicate leaf securing means including two main leaf retaining devices. These devices are engaged by the leaves of the pad 2 in such a manner as to permit the leaves to be moved 70 from recording position, where they lie to the right of the devices 4, as illustrated in Fig. 1, to stored position, where they lie to the left of the devices 4. One set of leaves 5, is indicated in stored position. 75

Each of the devices 4 comprises a metal loop, or hoop, rounded in cross-section, 80 standing from and fastened to the support 1. As illustrated each loop is made in sections, the upper section 6 being a substantial semi-circular part, one end of which is 85 hinged at 7 to the companion section, the opposite ends of the two sections coming together to complete the loop and being separably joined where the ends meet. For the purpose of holding the meeting ends in operative engagement with each other, the hinged section 6 has a tooth 6' on its side which cooperates with a like tooth 7' on the side of the lower section to effect the interlocking of the sections together, the hinge 7 permitting slight lateral play of the hinged section for permitting the ends of the sections to pass each other to permit interlocking engagement between said teeth. The 90 interlocking devices so provided prevent initial opening movement of the hinged section in the plane of the loop, the hinged section requiring slight lateral movement to free the teeth 6' and 7' from operative engagement with each other. Thus the sections 6 are movable to open and close the loops, and when the loops are open the leaves of the pad 2 may be engaged with the loops through the instrumentality of the apertures 95 8 in the leaves, these apertures being somewhat larger in diameter than that of the bar of which the loops are composed so as to per-

100
105

mit free movement of the leaves along the loops. In the form illustrated the lower sections of the loops are brazed or soldered to a plate 9 which may be riveted or otherwise fastened to the upper face of the support 1.

Supplementary retainers are provided to hold the leaves of the pad 2 elsewhere than at the ends which indicate the loops. In the form illustrated one supplementary retainer comprises a clip, spring-pressed and co-operating to bind the leaves against the support 1. One of these clips is illustrated at the right (Fig. 1) and includes a yoke the cross-piece 10 of which contacts with the end margins of the leaves of the pad 2 through the instrumentality of the bowed portion 11 of this cross-piece. The legs 12 of this yoke have feet loosely entering apertures 13 in the support 1, the feet comprising bent portions of the legs 12. The numerals 14 indicate flat metallic members pinned or otherwise fastened to the support 1, as by being riveted, and having free resilient ends 15 overlying the legs 12 and co-operating to press the legs, and consequently the bowed part of the cross-piece 10, toward the support 1.

Another supplementary retainer is illustrated at the left (Fig. 1) holding the set of leaves 5 in stored position. This supplementary retainer includes a spring-pressed pivoted yoke, the legs 16 of which are adapted to lie at opposite sides of the stored record leaves, the cross-piece 17 of this yoke being adapted to lie against the then upper face of the stored leaves and at a substantial distance from the free ends of said leaves. To conveniently provide for the placing of the inscribed leaves in stored position, the yoke member therefor is provided by a rectangular frame of which the outer sides are formed by the legs 16. One side 18 (Fig. 4) of this rectangular frame is pivotally mounted on the support 1, being held thereon for rotation by the bearing caps 19 fastened to the support. The side 18 has an offset portion or lug 20 engaged by a leaf spring 21 pinned to the support. The side of the frame opposite the pivoted side 18 provides the yoke cross-piece above referred to and is movable toward the support under the influence of the spring 21. The relation between the spring 21 and the offset 20 in the side 18 is such that the spring will tend to move the cross-piece 17 in either of opposite directions from the position assumed when the plane of the yoke is perpendicular to the supporting plate 1.

The numerals 22 indicates a finger piece, or button, laterally projecting from the rectangular frame and by means of which the frame may be rotated upwardly toward the left from the position indicated in full lines in Fig. 1 to the dotted line position, in which

latter position it will be yieldingly held by the spring 21. A slight turn of the frame either to the right or the left from the dotted line position will permit the spring 21 to rotate the arm either to the position indicated in full lines where it is adapted to lie against the stored leaves, or to the position indicated by the dotted lines 25, in which latter position the cross-piece 17 is out of the way of the leaves being stored. In the embodiment illustrated the rectangular frame referred to is formed from an integral rod bent to rectangular shape and so as to provide the offset 20. This rod may be extended at one side to provide the finger piece 22.

Provision is made for efficiently retaining various implements of use in connection with the log. The numeral 26 indicates a stiff shield or plate the ends of which are fastened to the support 1 the intermediate portion of this shield being spaced from the support to provide a chamber. Within this chamber is an implement bed adapted to retain a pencil, pen or other tool. In the present embodiment the implement bed is composed of interlaced fibers into which an implement, such as a pencil, may be readily thrust and held. The interlaced fibers may be provided by lining the inside of the chamber with a fabric 27 having a long pile as indicated at 28, oppositely projecting, the long fibers of the fabric interlacing or forming a mat adapted readily to receive and frictionally grip the implement. Besides overlying and protecting the implement bed, the shield 26 rises from the support 1 in front of the main retaining devices 4, and thus in front of the unused leaves of the pad 2 so as to screen the unused leaves from the influence of currents of air coming toward this end of the pad. In this wise the leaves are more readily retained in flat operative position.

In the present embodiment the pad 2 comprises a plurality of sets of five leaves each, although it is to be understood that a greater or less number of leaves may be employed. Each set of leaves includes four leaves 30 of soft paper and a leaf 31 of relatively hard paper, both kinds of paper being preferably durable and opaque. The four leaves 30 are formed from two superposed sheets double the length of a leaf, the sheets being folded intermediate their ends along the line 32 to provide four superposed leaves, each of these four leaves being preferably coated with transfer material on their under faces, so that inscription made upon the soft top or original leaf shall be transferred to the underlying soft leaves and also to the hard bottom leaf 31. The leaf 31, being hard, is not only very durable, but also serves as a stop leaf to prevent the transfer of inscription to any leaves lying thereunder. Each

of the leaves 30 and 31 is provided with the apertures 8 hereinbefore referred to to engage the loops 6. In Fig. 1, portions of the stored set of leaves are broken away to dis-
5 close the carbon transfer material with which the backs of the leaves 30 are coated.

Because of the use of the log in the open as at sea or in the air, it is desirable to securely hold all parts of the instrument, especially the record leaves. As assisting to this end the plurality of sets of leaves going to make up the pad 2 are removably secured together at their advance edges by a facing 35 of net fabric adhesively applied over this 15 end of the pad. In this wise not only are the sets of leaves secured together in a manner to permit their ready detachment by breaking the fabric of the netting, but the free ends of the leaves of each set are se-
20 cured to each other in a manner substantially air-tight and so as to prevent the air from getting under the leaves and lifting them up. On the end of the set of leaves 5, in stored position, the fabric 35 is depicted, it 25 having been broken away from the adjacent end of the pad 2.

The numeral 40 indicates a cutting tool, as a pencil sharpener blade, supported from the under face of the support 1, the numeral 41 30 indicating a hollow cylinder or guide for the end of the pencil. The numerals 42 and 43 indicate straps by means of which the log may be secured in convenient position for inscription. The straps may be bound to 35 the leg of the operator or to a suitable relatively stationary part of the vehicle and may pass loosely through suitable keepers 45 on the bottom of the support 1.

In operation the pivoted sections 6 of the 40 loops will be opened and the apertures 8 in the leaves of the pad engaged with the loops. Thereupon the pivoted sections will be closed, and the bow 11 of the yoke piece 10 manipulated to lie upon the top of the 45 pad near its margin. The log may now be strapped in operative position, as on the knee of the operator, and inscription made. In the present embodiment five copies of the inscription are made at one writing. After 50 inscription the inscribed leaves are removed from beneath the bow 11 and these leaves, as it were, rotated and moved along the loops until they lie upon the shield 26, the rectangular frame having been first moved 55 to the position indicated by the dotted lines 25. Thereupon the rectangular frame is rotated to the right (Fig. 1) into position bringing the cross-piece 17 down on the inscribed leaves in stored position, thus holding 60 the leaves. Inscription upon the next succeeding set of record leaves may then be made without further manipulation of the log.

It is to be understood that the record 65 leaves may be plain or provided with printed

data relative to the purpose in hand, and that suitable weakened lines may be provided to facilitate tearing the leaves apart along any desired lines.

Thus by the above described construction 70 are accomplished among others the objects hereinbefore referred to.

As many changes could be made in the above construction and many apparently 75 widely different embodiments of this invention could be made without departing from the scope thereof, it is intended that all matter contained in the above description or shown in the accompanying drawings shall be interpreted as illustrative and not in a 80 limiting sense.

It is also to be understood that the language used in the following claims is intended to cover all of the generic and specific features of the invention herein de- 85 scribed and all statements of the scope of the invention, which, as a matter of language, might be said to fall therebetween.

Having described my invention, what I claim as new and desire to secure by Letters 90 Patent, is:

1. A recording device including, in combination, a plurality of sets of superposed record leaves and material for transferring inscription on an upper leaf of a set to the 95 underlying leaves thereof, each of said sets including a sheet folded to provide superposed leaves, and means adapted to secure the free ends of said leaves to each other.

2. A recording device including, in combination, a plurality of sets of superposed record leaves and material for transferring inscription on an upper leaf of a set to the underlying leaves thereof, each of said sets including a sheet folded to provide super- 100 posed leaves and means adapted to secure the free ends of said leaves to each other, said leaves having apertures adapted to register with each other.

3. A record device including, in combina- 110 tion, a plurality of sets of superposed record leaves and material for transferring inscription from an upper leaf of a set to the underlying leaves thereof, each set includ- 115 ing a sheet folded to provide superposed leaves, said sheets being attached together at the free ends to form a pad and each of said sets comprising also additional sheets held within said folded sheet.

4. A record device including, in combina- 120 tion, a plurality of sets of superposed record leaves and material for transferring inscription from an upper leaf of a set to the underlying leaves thereof, each set including a sheet folded to provide superposed leaves, 125 said sheets being attached together at the free ends to form a pad and each of said sets comprising also additional sheets held within said folded sheet, and a backing, said sheets having apertures adjacent to their at- 130

tachment, ring supports upon said backing for engagement with said apertures whereby the set of record leaves may be moved from recording position to storing position 5 as a unit by rotation upon said rings.

5. A record device including, in combination, a plurality of sets of superposed record leaves and material for transferring inscription from an upper leaf of a set to the 10 underlying leaves thereof, each set including a sheet folded to provide superposed leaves, said sheets being attached together at the free ends to form a pad and each of said sets comprising also additional sheets held 15 within said folded sheet, and a backing, said sheets having apertures adjacent to their attachment, ring supports upon said backing for engagement with said apertures whereby the set of record leaves may be 20 moved from recording position to storing position as a unit by rotation upon said rings, and means upon said backing for re-

taining the sets in position both in the stored and in the unstored position.

6. A pad of record leaves for an aviator's 25 log including a plurality of sets of leaves bound together to form a pad, manifolding material between said leaves to transfer inscriptions from an upper leaf to a lower, the free ends of each set being attached to- 30

gether. 7. A pad of record leaves for an aviator's 35 log including a plurality of sets of leaves bound together to form a pad, manifolding material between said leaves to transfer inscriptions from an upper leaf to a lower, the free end of each set being attached to- 40

gether and a stiff sheet between each of said sets and manifolding material adapted to transfer inscription from said first men- 45

tioned leaves to said stiff sheet.

In testimony whereof I affix my signature.

C. W. GILLER
